CLAIM

(57) The ornamental design for a composter, substantially as shown and described.

DESCRIPTION

FIG. 1 is a front, top, left perspective view of my design for a composter according to the present specification;

FIG. 2 is a left side elevational view of FIG. 1;

FIG. 3 is a right side elevational view of FIG. 1;

FIG. 4 is a rear elevational view of FIG. 1;

FIG. 5 is a front elevational view of FIG. 1;

FIG. 6 is a top plan view of FIG. 1;

FIG. 7 is a bottom plan view of FIG. 1; and,

FIG. 8 is a front, top, left perspective exploded view of FIG. 1.

The broken lines in the drawings depict portions of the composter that form no part of the claimed design.
